[57] **CLAIM**

The ornamental design for a multiple compartment trash receptacle, as shown and described.

DESCRIPTION

FIG. 1 is a top and front perspective view of a multiple compartment trash receptacle showing my new design, the one of the compartment with its lid open for clarity of illustration;

FIG. 2 is a top plan view thereof;

FIG. 3 is a front elevational view thereof;

FIG. 4 is a side elevational view thereof, the opposite side view being a mirror image of that shown; and

FIG. 5 is a bottom plan view thereof.

FIG. 1**FIG. 2**
